(57) **CLAIM**

The ornamental design for an inverter for vehicle, as shown and described.

DESCRIPTION

FIG. 1 is a perspective view of an inverter for vehicle showing my new design in a first state;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof; and,
FIG. 8 is a perspective view thereof, shown in a second state. The broken lines shown illustrate portions of the inverter for vehicle that form no part of the claimed design.
